(57) CLAIM

The ornamental design for a bag handle cover as shown and described.

DESCRIPTION

FIG. 1 is a front elevation view of a bag handle cover showing my new design.

FIG. 2 is a rear elevation view of the bag handle cover.

FIG. 3 is a left side elevation view of the bag handle cover.

FIG. 4 is a right side elevation view of the bag handle cover.

FIG. 5 is a top plan view of the bag handle cover; and,

FIG. 6 is a bottom plan view of the bag handle cover.

The dot-dash broken lines define the bounds of the claimed design and form no part thereof. The dash-dash broken lines depict portions of the bag handle cover that form no part of the claimed design.

1 Claim, 2 Drawing Sheets
